UNITED STATES PATENT OFFICE.

WILLIAM A. PURDY, OF MANCHESTER DEPOT, VERMONT.

HEN NEST.

Application filed June 29, 1922. Serial No. 571,704.

To all whom it may concern:

Be it known that I, WILLIAM A. PURDY, a citizen of the United States, residing at Manchester Depot, in the county of Bennington, State of Vermont, have invented a new and useful Hen Nest; and I do hereby declare the following to be a full, clear, and exact description of the invention, such as will enable others skilled in the art to which it appertains to make and use the same.

The invention relates to hen nests and has for its object to provide a device of this character formed from sheet metal and provided with a removable bottom whereby the nest may be easily cleaned, and at the same time be practically vermin proof.

A further object is to provide a metallic hen nest having a curved upper side, either front or rear, so constructed that a fowl cannot roost on the same, and consequently preventing a collection of droppings on the nest. Also to provide hangers, preferably curved brackets having screw receiving slots in the upper ends thereof forming means whereby the nest may be easily and quickly attached to supporting headed members and removed therefrom.

A further object is to provide sides of the nest with ventilating openings, preferably located above the nest entrance.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

40 In the drawing:

Figure 1 is a front elevation of adjacent hen nests, one of said nests being broken away.

Figure 2 is a vertical transverse sectional view through the hen nest.

Figure 3 is a detail view showing in front elevation one corner of a hen nest.

Referring to the drawing, the numeral 1 designates adjacent hens' nests which are formed from sheet metal thereby allowing the nests to be easily cleaned and also preventing the collection of vermin. Each nest 1 comprises the side members 2, the outwardly and downwardly curved front 3, on which, on account of its inclination fowl cannot roost, the back wall 4 and the hori-

zontally disposed flange 5 which supports the removable bottom 6. The inclined wall may be curved inwardly or outwardly as desired. The flange 5 also forms an opening 7 in the bottom of the nest through which opening when the removable bottom 6 is pulled outwardly by grasping the finger engaging member 8, the contents of the nest will fall when it is desired to renew the nest material and thoroughly clean the nest. If so desired the back wall may be eliminated or be removed in which case the bottom 6 may be removed through the back of the nest. The forward end of the removable bottom 6 when in place as shown in Figure 2 underlies the lower edge of the front 3 of the nest, therefore it will easily slide outwardly on the flange 5.

The flange 5 is formed integral with the body of the nest, however it is to be understood that they may be riveted or otherwise secured thereto. By forming the nest entirely of metal, it is obvious that the collection of vermin in cracks and the like is obviated, which is one of the main objections against wooden nests. It will also be seen that the nests may be submerged in a solution for killing vermin without damaging the nest. The forward wall 3 is provided with an entrance 9 whereby fowl may have ingress and egress to the nest.

The side walls 2 are provided with ventilating openings 10, which are preferably located above the upper side 11 of the entrance 9 and forms means whereby the upper portion of the nest will be thoroughly ventilated as well as the bottom portion. The nest is supported on a vertical support 12 by means of segmentally shaped brackets 13, which engage the outer wall of the front wall 3 and are provided with inwardly extending horizontally disposed arms 14, which underlie the bottom of the nest and overlie the forward end of the removable bottom 6, not only supporting the nest but at the same time holding the removable bottom 6 against accidental displacement. The upper ends of the brackets 13 terminate in vertically disposed portions 15, which portions are provided with slots 16 for the reception detachably of headed members 17, therefore it will be seen that the nest may be easily and quickly attached to a support 12 in such a manner that the nest may be easily and quickly removed for cleaning purposes, such for instance as where it is de-

sired to submerge the entire nest in a solution for killing vermin.

The invention having been set forth what is claimed as new and useful is:—

- 5 A hen nest formed from sheet metal, said nest having its front wall curving outwardly and downwardly and provided with an entrance passage, a flanged opening in the bottom of the nest, a removable sheet metal
- 10 bottom horizontally disposed and supported on said flanges of the flanged opening, the outer end of the removable bottom underlying the lower end of the front wall of the nest, curved supporting brackets adjacent
- 15 the ends of the nest and engaging the outer

side of the front wall, the lower ends of said brackets overlying the front ends of the removable bottom and terminating in inwardly extending arms underlying the bottom of the nest, the upper ends of the 20 brackets being provided with means whereby they may be detachably connected to a vertical support.

In testimony whereof I have signed my name to this specification in the presence of 25 two subscribing witnesses.

WILLIAM A. PURDY.
